UNITED STATES PATENT OFFICE.

ALONZO RUSSELL AND ANDREW J. RUSSELL, OF BURR OAK, MICHIGAN.

FENCE.

SPECIFICATION forming part of Letters Patent No. 267,596, dated November 14, 1882.

Application filed July 14, 1882. (No model.)

To all whom it may concern:

Be it known that we, ALONZO RUSSELL and ANDREW J. RUSSELL, both of Burr Oak, in the county of St. Joseph and State of Michigan, have invented a new and useful Improvement in Fences, of which the following is a full, clear, and exact description.

This invention relates to that class of fences that occupy a comparatively small space in width, that are set up without the necessity of digging holes, and that are firm both longitudinally and transversely.

The nature of the invention consists of posts, side stakes, longitudinal rails, and braces, all wired together, substantially as hereinafter more fully set forth.

Reference is to be had to the accompanying drawings, forming a part of this specification, in which similar letters of reference indicate corresponding parts in all the figures.

Figure 1 is a perspective view of our improved fence. Fig. 2 is a detail view, showing the connection of the tightening braces to the posts and stakes. Fig. 3 is a transverse section, showing the support of the upper rail.

The fence may be constructed of boards, of ordinary fence-rails, or of split timber, and of any height as desired.

A A are perpendicular posts, resting at their lower ends upon the ground.

B B are side stakes or braces, the ends of which may be set in the ground or not. The post A and the stakes B B are secured together at the top by wires, as shown at a, and between the upper ends of the stakes B there may be a rider, E, as shown, secured by the same wire. C C are the tightening-stakes, which also serve as lengthwise braces of the fence. These stakes pass at their upper end into the loop of the

wire a, as shown most clearly in Fig. 2, and 40 being inserted in a horizontal position, and their outer end then moved down to the position shown in Fig. 1, the wire a is tightened. The lower ends of the stakes C are then to be secured by wires, as shown at b, to the lower 45 rails of the fence.

D D are the rails of the fence. The upper rails D are held in place by being wired to the posts A and stakes B, as shown at d. The other rails are suspended from this top rail by 50 loops of wire, and they may be placed a greater or less distance apart, according to requirements. The rails are also wired to the vertical posts A. The posts A serve to prevent the fence from settling, so that it shall retain its 55 place upon soft ground. The lengthwise braces C are to be placed two running in one direction, and then two in the opposite direction, so that the fence will be firmly braced lengthwise, and cannot be thrown down by wind or 60 by cattle. The stakes B prevent the fence from being thrown over sidewise.

This fence may be readily set up and taken down, and requires a comparatively small amount of material to make a strong, durable, 65 and close fence.

Having thus described our invention, we claim as new and desire to secure by Letters Patent—

The fence consisting of the posts A, the side 70 stakes, B, the longitudinal rails D, and the braces C, the parts being wired together substantially as shown and described.

ALONZO RUSSELL.

ANDREW JACKSON RUSSELL.
